UNITED STATES PATENT OFFICE.

NORMAN C. BASSETT, OF PHILADELPHIA, PENNSYLVANIA.

METALLIC PACKING FOR PISTON-RODS.

SPECIFICATION forming part of Letters Patent No. 271,300, dated January 30, 1883.
Application filed November 16, 1882. (No model.)

To all whom it may concern:

Be it known that I, NORMAN CHAUNCEY BASSETT, of the city and county of Philadelphia, of the State of Pennsylvania, have invented a new and useful Improvement in Metallic Packings for Piston-Rods; and I do hereby declare the same to be described in the following specification and represented in the accompanying drawings, of which—

10 Figure 1 is a vertical section of parts of a piston-rod and steam-engine cylinder with my improved packing applied thereto. Fig. 2 is a top view of one ring of the inner series of metallic rings. Fig. 3 is a top view of one ring 15 of the outer series of metallic rings.

The nature of my invention is defined in the claims hereinafter presented.

In Fig. 1 the piston-rod is shown at A and the cylinder-head at B, the latter having within it a cylindrical chamber, a, to receive the parts or rings of the packing. Leading from the bottom of such chamber to the bottom of the head, and concentric with the piston-rod, is a cylindrical passage, b, having a diameter 25 a little greater than that of the said rod, and there is screwed into the chamber, at its mouth, a cap or "gland," C; having in its central part a cylindrical passage, c, whose diameter is a little larger than that of the rod. Within the 30 said chamber I use in the formation of the packing two series of flat rings, each one of the inner series being marked D, while each one of the outer series is marked E. Each ring E has made down within it, concentrically, a cylindrical chamber, d, having a depth 35 equal to or a trifle greater than that of the ring D, placed in it, such chamber also having a diameter somewhat greater than that of the said ring. The rings E rest upon one another, or are arranged in manner as shown 40 within the chamber a, each of such rings having within its chamber one of the rings D. The lowest ring D, and perhaps one or more others of the series to which it belongs, I provide with holes e, leading upward through it 45 from the passage b and terminating in an annular groove, f, made concentrically in the top

of the ring, and equal or about equal in sectional area to that of the passage b.

Resting on the uppermost of the rings D 50 and E is a conical ring, F, between which and the gland C, and in contact with both, is an elastic or yielding ring, G, of asbestos or vulcanized india-rubber or other suitable material.

In and around each of the wearing-surfaces 55 of the several rings D and E, I usually have one or more grooves, h, for water to collect in, and seal the joint between such surface and that next adjacent to it.

From the above it will be seen that the rings D, while serving in part as a packing to the piston-rod, can move laterally with it in the rings E, held in place by the rings F G and the gland C; also, that the pressure of the 60 steam exerted through the passage b against the lower surface of the lowermost ring D will be counterbalanced by that of the steam that may pass through the passage e into the groove f; also, that the upward pressure of such steam 70 on the ring E covering such groove will be resisted by the elastic ring G, which will also allow the ring D to move laterally when fitting closely to the rings E.

A piston-rod packing can thus be made 75 which will operate to excellent advantage and be very durable and sufficiently steam-tight and yielding relatively to the rod.

I do not claim a packing composed of a series of internal rings and a series of chambered rings constructed and arranged as represented in either of the United States Patents Nos. 222,805 or 228,200. Nor do I claim an elastic annulus constructed and arranged with packing-rings, as represented in the latter of 85 said patents, my invention involving, in connection with such an annulus and two series of rings, as hereinbefore described, the conical ring F, whereby when the gland is screwed down the elastic annulus is pressed outward 90 as well as compressed.

I claim—

1. The combination of the conical ring F and the yielding or elastic ring G, arranged

in the chamber *a*, with the gland *C* thereof, and with the two series of rings *D* *E*, constructed, arranged, and adapted in manner and for use with a piston-rod, *A*, substantially as set forth.

2. The gland *C* and the chamber *a*, provided with the passages *c* and *b*, arranged as explained, in combination with the rings *F* and *G* and the series of chambered rings *E* and

their series of internal rings, *D*, having to the 10 lowermost of them (the said rings *D*) the passage *e* and annular groove *f*, arranged in it, as explained.

NORMAN CHAUNCEY BASSETT.
